Primary Examiner — Mark T. Philippss

CLAIM

The ornamental design for a cutting insert for machine tools for metalworking as shown and described.

DESCRIPTION

1. Cutting insert for machine tools for metalworking

1.1 : Perspective

1.2 : Front

1.3 : Back

1.4 : Top

1.5 : Bottom

1.6 : Left

1.7 : Right

The design features a decagonal shape that extends in the transverse direction in the top view. The transverse width is greater than the longitudinal width. There is a protrusion that extends diagonally to opposite corners. In the front view, the overall outline appears rectangular with additional vertical sections. Vertical lines divide the front face into sections, with two prominent vertical lines near the center and additional vertical lines towards the sides. The left and right edges of the shape have small, rounded cut-outs near the top.
